CLAIM

We claim, the ornamental design for a thermal bowl with handle, as shown and described.

DESCRIPTION

FIG. 1 is a perspective view of a thermal bowl with handle, showing my new design;

FIG. 2 is a top view thereof;

FIG. 3 is a bottom view thereof;

FIG. 4 is a side view thereof;

FIG. 5 is side view thereof, taken opposite from FIG. 4;

FIG. 6 is front view thereof; and,

FIG. 7 is a rear view thereof.

The broken lines depict portions of the thermal bowl with handle that form no part of the claim.
